UNITED STATES PATENT OFFICE.

MARY E. WATSON, OF INDIANAPOLIS, INDIANA, ASSIGNOR TO DIXIE COTTON FELT MATTRESS COMPANY, OF CHICAGO, ILLINOIS, A CORPORATION.

MATTRESS.

1,202,131.

Specification of Letters Patent.

Patented Oct. 24, 1916.

Application filed January 10, 1914. Serial No. 811,425.

To all whom it may concern:

Be it known that I, MARY E. WATSON, a citizen of the United States, and a resident of Indianapolis, county of Marion, State of Indiana, have invented certain new and useful Improvements in Mattresses, of which the following is a full, clear, and exact description.

The invention relates to mattresses and 10 seeks to provide simple and effective means for strengthening or bracing the tick or covering of the mattress, so that the mattress will not stretch or get out of shape.

The invention consists in the features of 15 improvement hereinafter set forth, illustrated in different forms in the accompanying drawings and more particularly pointed out in the appended claims.

In the drawings, Figure 1 is a perspective 20 view of a mattress embodying the present improvement. Fig. 2 is a view of the inner face of a mattress tick or covering, showing the strengthening braces applied thereto, portions of the braces being broken away to 25 more clearly show the folds in the covering. Fig. 3 is a partial perspective view illustrating a modified form. Fig. 4 is a view 30 of the inner face of the covering shown in Fig. 3. Fig. 5 is a view similar to Fig. 4 illustrating a further modification.

The mattress tick is formed, as usual, of a top covering *a* and a similar bottom covering which is connected to the top covering by a side or edge wall *b*. The edge wall *b* 35 is sewed to the side and end edges of the top and bottom coverings. The mattress may be filled with any suitable material, such as layers of cotton felt. The filling material is held in place by rows of tufts *c* which are 40 preferably arranged to produce biscuit forms upon the surface of the mattress.

As usual, the dimensions of the top, bottom and edge coverings *a* and *b* exceed somewhat the dimensions of the finished mattress, the fullness in the tick or covering being taken up in the tufting operation and by the take-up stitches which extend from the side or edge walls of the mattress to the top and bottom coverings thereof. This necessary fullness of the top and bottom coverings to allow for the tufting, permits the stretching of the mattress when in use, and particularly if the tufting breaks. In use, this stretching occurs chiefly in lateral direction, that is to say, in a direction at right

angles to the length of the mattress. To prevent this stretching, the top and bottom coverings are each provided with a series of flat, transverse, bracing straps *d* which extend at regular intervals across the inner 60 faces thereof and which are sewed to the coverings. As indicated in the drawings, these straps are preferably sewed to the coverings by rows of stitches 1 that extend lengthwise of the straps and adjacent 65 the edges thereof.

The transverse bracing straps *d* preferably extend entirely across the tick or covering *a*, the length of each strap being substantially equal to the width of a finished 70 mattress. Inasmuch as the width of the covering *a* is greater than that of the finished mattress, tucks or folds must be formed therein in order to permit the application of the straps thereto. The trans- 75 verse straps are arranged, as shown, between the transverse rows of tufts *c* and, in the form shown in Figs. 1 and 2, the covering *a* is provided, between the tufts, with a number of series or rows of diagonal, intersecting folds or plaits 2 across which the straps *d* extend. 80

While, as stated, the mattress in use tends to stretch much more in lateral than in longitudinal direction, the top and bottom coverings *a* are also preferably provided with a series of straps *e*, similar to the transverse straps *d*, which extend across the inner face of the covering between the longitudinal rows of tufts. The tucks 2 are formed in 85 the top and bottom coverings *a* and the transverse and longitudinal series of bracing straps *d* and *e* are applied to the inner faces thereof before the coverings are united to the edge wall *b* to form the tick. Preferably, the diagonal tucks 2 are formed in 90 the covering before the straps are sewed thereon, and the previously formed tucks are held in place until the straps are applied by stitches 3. The cross marks 4 in Fig. 2 100 indicate the points at which the tufting stitches are formed after the complete tick is filled with suitable material, such as cotton felt or the like.

It should be noted that the tucks 2 and the 105 bracing straps *d* and *e* are arranged between the rows of tufts, so that ample fullness is provided in the top and bottom coverings for the tufting operation. At the same time, the straps serve to retain the shape of the 110

mattress and prevent it from stretching, even though the tufting stitches may be broken. The bracing straps are formed of non-elastic material and preferably of the same material as the covering or tick. The straps *d* and *e* are cut from the material, so that the warp threads run lengthwise thereof and when the transverse straps are sewed in place, these warp threads, which are stronger than the weft threads, extend across or at right angles to the warp threads of the covering. In this way, the transverse stretching of the tick covering is effectively prevented and at the same time sufficient fullness is provided for the tufting stitches.

The form shown in Figs. 3 and 4 is similar to that shown in Figs. 1 and 2, except that the top and bottom coverings *a* are provided with a number of rows or series of tucks or folds 5 which extend in longitudinal and transverse direction between the tufts and the diagonal folds, such as shown in Figs. 1 and 2, are omitted. In this form, the folds are arranged at right angles to the straps *d* and *e* and to the rows of stitches 1, and the folds may be formed in the covering as the straps are sewed thereto. For this reason, it is not necessary to preliminarily sew the folds in place before the straps are applied.

The form shown in Fig. 5 is similar to that shown in Fig. 4, except that the longitudinal straps and the transverse folds are omitted.

It is obvious that numerous changes may be made in the details set forth without departure from the essentials of the invention as defined in the claims.

I claim as my invention:—

40 1. A mattress or the like having a cover and rows of tufts, said cover having a series of folds formed therein to provide fullness for said tufts, and a series of bracing straps extending at intervals over and in contact with said cover and securely sewed thereto, said straps extending across said folds between the ends thereof and maintaining the formation of the same.

45 2. A mattress comprising an outer ticking, suitable filling material and rows of tufting stitches for holding the said filling material in place, the top and bottom portions of said ticking having a series of longitudinal folds to provide fullness for said tufting stitches, and a series of transverse bracing straps extending at intervals across and stitched substantially throughout their lengths to the faces of the top and bottom portions of said ticking, said straps extending across said folds at an angle thereto, and maintaining the formation of the same.

50 3. A mattress provided with top and bottom coverings and with rows of tufts, said coverings having rows of tucks formed therein between said tufts, and a series of

bracing straps extending over and securely stitched to the inner faces and the tucks of said coverings, substantially as described.

4. A mattress provided with top and bottom coverings and with transverse rows of tufts, and a series of flat, transverse straps extending across and sewed substantially throughout their lengths to the inner faces of said coverings and arranged between said rows of tufts, said coverings having rows of tucks formed therein between said tufts and over which said straps extend at an angle thereto, substantially as described. 70 75

5. A mattress provided with top and bottom coverings and with longitudinal and transverse rows of tufts, and a series of intersecting, transverse and longitudinal bracing straps extending over and stitched substantially throughout their lengths to the inner faces of said coverings and arranged between said rows of tufts, substantially as 80 85 described.

6. A mattress or the like having a cover, portions of which are folded to inwardly project, and lines of stitching extending transversely of such folded portions between the ends thereof and maintaining the formation of the same. 90

7. A mattress or the like having a cover, portions of which are folded to inwardly project, and lines of stitching extending transversely of such folded portions between the ends thereof and maintaining the formation of the same; reinforcements being provided for the cover and being coextensive 100 with the lines of stitching. 95

8. A mattress or the like having a cover, portions of which are folded to inwardly project, and lines of stitching extending transversely of such folded portions and 105 maintaining the formation of the same; said cover being provided with tufts between which the cover folds extend, and said lines of stitching being arranged to intersect the folds intermediate of the tufts. 110

9. A mattress or the like having a cover, portions of which are folded to inwardly project, and lines of stitching extending transversely of such folded portions and maintaining the formation of the same; said 115 cover being provided with tufts between which the cover folds extend, and said lines of stitching being arranged to intersect the folds intermediate of the tufts; reinforcements being provided for the cover and being co-extensive with the lines of stitching. 120

10. A mattress or the like, comprising a case consisting of top and bottom covers and side or edge covers joined therewith, and a filler for the case, said top and bottom covers 125 being provided each with tufts, means being provided uniting said tufts and extending through said body or filler and depressing the tufts with respect to the body, each of said top and bottom covers being pro- 130

vided with inwardly projecting folds extending between the tufts and with rows of stitching intersecting the folds at points between the tufts.

5 11. A mattress or the like, comprising a case consisting of top and bottom covers and side or edge covers joined therewith, and a filler for the case; said top and bottom covers being provided each with tufts, means being provided uniting said tufts and extending through said body or filler and depressing the tufts with respect to the body; each of said top and bottom covers being provided with inwardly projecting folds extending 10 between the tufts and with rows of stitching intersecting the folds at points between the tufts; inelastic reinforcements being provided for the cover and joined thereto by said rows of stitching and being co-extensive 15 with said rows of stitching.

12. A mattress comprising an outer ticking and a suitable filling material and having a series of longitudinal and transverse rows of tufts, the top and bottom portions of 25 said ticking having a series of folds extending longitudinally of the mattress in alignment with the tufts forming the longitudinal rows to provide fullness for the tufts, and a series of straps stitched substantially 30 throughout their length to the top and bottom portions of the ticking, said straps ex-

tending transversely of the mattress between the transverse rows of tufts and extending across said folds intermediate their ends.

13. A mattress comprising an outer ticking and a suitable filling material and having a series of longitudinal and transverse rows of tufts, the top and bottom portions of said ticking having a series of rows of 35 longitudinal and transverse folds in alignment with the respective longitudinal and transverse rows of tufts to provide fullness for the tufts, and a series of longitudinal and transverse straps stitched to the top and bottom portions of said ticking between the 40 rows of tufts, the transverse straps being stitched across the longitudinal folds and the longitudinal straps being stitched across the transverse folds intermediate the ends of the folds.

14. A mattress comprising an outer ticking and a suitable filling material and having longitudinal and transverse rows of tufts, and inelastic bracing straps equal in length to the width of the finished mattress stitched substantially throughout their 55 length to the top and bottom portions of the ticking between the transverse rows of tufts.
